THREADED FASTENER

Hilmar K. Dieme, Westfield, N.J., assignor to
Amerace Corporation, New York, N.Y.

Filed Nov. 16, 1973, Ser. No. 416,440

Term of patent 14 years

Int. Cl. D8—08

U.S. Cl. D8—273

FIG. 1

FIG. 2

FIG. 3

FIG. 4FIG. 7FIG. 5FIG. 8FIG. 6FIG. 9

FIG. 1 is a top plan view of a threaded fastener in the form of a lug nut showing my new design;

FIG. 2 is an elevational view thereof;

FIG. 3 is a bottom plan view thereof;

FIG. 4 is a top plan view of a threaded fastener in the form of a lug nut showing still another embodiment of my new design;

FIG. 5 is an elevational view thereof;

FIG. 6 is a bottom plan view thereof;

FIG. 7 is a top plan view of a threaded fastener in the form of a cap nut showing a further embodiment of my new design;

FIG. 8 is an elevational view thereof; and

FIG. 9 is a bottom plan view thereof.

I claim:

The ornamental design for a threaded fastener, as shown and described.
